MUCKING MACHINE DIPPER HOISTING
MEANS

William A. Whitmire, Boca, Calif.

Application August 4, 1937, Serial No. 157,331

8 Claims. (Cl. 214—134)

This invention, a mucking machine dipper hoisting system presents as its main feature a hoisting system for excavating and mucking machine dippers which automatically compensates for the advance and retraction of the crowd, paying out and taking up the hoisting cable in conformity with the movements of the crowd, whereby the dipper is maintained on an even keel when the hoisting mechanism is not operating to raise or lower the dipper, and thereby facilitates and simplifies the operation of mucking, increasing efficiency and reducing costs of mucking.

This invention is an improvement over my Patent No. 2,086,687, issued July 13, 1937, and may be substituted for the hoisting mechanism shown therein, and also in conjunction with the improvements disclosed in my Patent No. 2,067,879, issued January 12, 1937, and my co-pending applications, Serial No. 157,330, filed Aug. 4, 1937, and Serial No. 157,332, filed Aug. 4, 1937, and respectively covering a mucking machine dipper, and, a mucking machine and conveyor system, and may also be incorporated in other rigid dipper arm types of mucking and excavating machines.

The objects and advantages of the invention are as follows:

First; to provide a self-compensating hoisting system which will automatically compensate for advance and retraction of the crowding means for a dipper.

Second; to provide a system of the type outlined which will maintain a dipper on an even keel, or in its instant existent relation to the crowd during advance and retraction of the dipper so long as the means for actual raising and lowering of the dipper is not placed in operation.

Third; to provide a hoisting system in which the compensating means is operated directly through the medium of the crowding means, whereby compensation will be automatic and positive in character.

Other objects and advantages of the invention will become apparent as the following description is read on the drawing forming a part of this specification, and in which similar reference characters are used to designate similar parts throughout the several views, of which;

50 Fig. 1 is a plan view of the invention.

Fig. 2 is a side elevation of Fig. 1.

The bucket or dipper 10, wrist joint 11, and the dipper stick arrangement 12 are shown in a type as disclosed in my patents and applications previously referred to, but the invention is not

limited to this specific arrangement, and can be used with other types of dippers and with dipper sticks or arms of rigid construction.

The bail 13 is pivoted to the sides of the dipper as indicated at 14, and the back-stop 15 for the bail has a specific function to perform when a pivoted bail is used in connection with the wrist joint, as will be hereinafter described.

The mucking machine has a carriage or supporting frame 16, and a mucking section frame 17 is swivelly supported thereon and includes a crowd 18 which is operated for advance and retraction by means of a pinion 19 cooperating with the rack 20 which is integral with the crowd 18, or affixed thereto. Any other suitable type of crowding means may obviously be substituted and the order reversed by having the rack drive the pinion when the crowd is fluid operated, as by a steam or air engine or by a hydraulic jack.

The pinion 19 is fixed on a shaft 21, and this shaft may be driven by any suitable power mechanism and reduction gearing, and is here shown as driven through a speed reducer 22, and chain or belt 23 operating over sprockets or pulleys 24 and 25, illustrating the drive arrangement in the simplest manner, since suitable drives and controls are well known in the art and require no detailed description.

A separate winch or hoisting drum shaft 26 is driven by suitable means, and is here shown as driven through a speed reducer 27, pulleys 28 and 29 and belt 30, the controls for the drive not being shown, since any conventional type of control may be used.

Mounted on the respective ends of shaft 26 are the respective hoisting drums 31 and 32. Two compensating drums 33 and 34 are respectively mounted on the respective ends of the pinion shaft 21 and have a diameter substantially twice the pitch diameter of the pinion, since the cable payout must be substantially twice the crowd movement to maintain the dipper on an even keel or in a uniform plane or position relative to the crowd as the crowd is advanced and retracted.

One cable 35 has one end secured to the drum 32 and is wound and unwound thereon for hoisting and lowering the dipper through the medium of the drive 27 to 30 which is suitably controlled by known means.

From this drum 32, the cable passes over a sheave 36 which is rotatable on shaft 37 mounted at the top of the frame, then continues down and about the sheave 38 which is rotatably supported on a shaft 39, which in turn is supported by the 55

links 40 connected to the bail 13 at 41. The cable then continues upwardly to and over a second sheave 43 which is also rotatable on the shaft 31, and thence down and about the drum 34 to which the other end of this cable is secured.

Another cable 44 has one end secured to the drum 31, passes over sheave 45, then about sheave 46, up and over sheave 47 and down to drum 33 to which the other end of the cable is attached.

With this arrangement, when the hoisting drums are stationary and the crowd is moved either forwardly or backwardly, the compensating drums rotate with the pinion and either take up or pay out the cable in just the right amount to maintain the relative position of the dipper and crowd.

Thus, when the crowd is driven forward by pinion 19, cables 35 and 44 are paid out from drums 34 and 33 at approximately twice the speed of movement of the crowd, and while the hoisting drums 31 and 32 are stationary, the bail sheave shaft 39 travels at the same speed as the crowd, and the dipper is maintained on an even keel or in the same relation to the crowd due to the fact that the bail is cooperating with the back stop 45 and thereby forms a long rigid lever arm measured from the wrist connection.

Latching means is provided for the dipper and consists of a latch 48 for each side of the dipper, pivoted at 49 and having a counterweight 50 at one end and a release arm 51 at the other end, and the latch cooperates with the cross bar 52 which is fixed to the cover 53 which is hinged at 54. Release members 55 are fixed on the frame 35 in cooperative relation to the arms 51, whereby as the dipper is hoisted to its highest position, at which point the dipper is inverted due to the action of the crossed dipper sticks 12, the arms 51 cooperate with the release members 55 and 40 release the cover to permit the muck to dump from the dipper. As the dipper is again lowered, the arms 51 are freed from stops 55 and the counterweight automatically causes the latch to engage and secure the cover in closed position.

The crowd may be advanced or retracted and the dipper coincidently raised or lowered by the hoisting means, or kept in the existent relation to the crowd merely by control of the hoisting drums, 31 and 32, which function the same, with 50 the same payout and takeup of cable, whether the crowd is moving or stationary, thus providing for accuracy of control and speed. The drums 33 and 34 function automatically to maintain an exact relation of dipper to hoisting drum 55 so far as hoisting cable movement is concerned, facilitating and simplifying operation of the machine and increasing efficiency and speed of operation.

It will be understood that variations in arrangement and construction of parts, which variations are consistent with the appended claims, may be resorted to without detracting from the spirit or scope of the invention, or sacrificing any of the advantages thereof.

I claim:

1. Dipper hoisting means for a mucking machine having a frame, a dipper, a crowd and driving means therefor, a hoisting drum and driving means therefor, a compensating drum operatively associated with said crowd, a pair of sheaves rotatably mounted on said frame, a single sheave associated with said dipper, and a cable having one end associated with said hoisting drum and its other end associated with said compensating drum, the intermediate portion of said cable

passing over one of said pair of sheaves, thence about said single sheave and thence over the other of said pair of sheaves, the payout of said cable from said compensating drum being substantially twice the advance movement of said crowd.

2. A hoisting system for a mucking machine having a crowd and operating means therefor, and a mucking section frame, a dipper having a bail and a sheave associated with said bail, a compensating drum operatively associated with said crowd, a hoisting drum and driving means therefor, a pair of sheaves rotatably supported on said frame, and a cable passing about said dipper sheave and the respective ends passing over the respective sheaves of said pair and to the respective drums.

3. A structure as claimed in claim 2, said bail being pivoted to said dipper, and a back stop for said bail to convert said bail into a rigid lever arm to increase the purchase when the dipper is in a lowered or partly lowered position.

4. A structure as claimed in claim 2, the operative association between said compensating drum and said crowd comprising a rack on said crowd, a pinion meshing with said rack, a shaft for said pinion, said compensating drum having a diameter substantially twice the pitch diameter of the pinion.

5. A hoisting system for a mucking machine having a crowd provided with a rack, and a pinion cooperating with said rack, and a shaft for said pinion, a dipper having a bail pivotally attached to the sides thereof, and back stop means for limiting the backward swing of said bail about its pivotal points to a position inclined forwardly of the point of pivotal attachment, said bail extending well above the top of the dipper for increased purchase, a mucking section frame, a single sheave associated with the upper end of said bail, a pair of sheaves rotatably supported on said frame, a hoisting drum and driving means therefor, a compensating drum mounted on said shaft and having a diameter substantially twice the diameter of said pinion, and a cable operating from said compensating drum over one of said pair of sheaves, about said single sheave and over the other of said pair of sheaves and to said hoisting drum, whereby said dipper is supported in a plane determined by said hoisting drum irrespective of the advance or retractive movements of said crowd.

6. A hoisting system for a mucking machine having a dipper provided with a bail and back-stop means for the bail, a crowd and driving means therefor and dipper sticks pivotally connecting the dipper to the crowd; comprising, a hoisting drum and driving means therefor; a compensating drum controlled and driven by said crowd and having a peripheral speed equal to twice the lineal speed of the crowd; a pulley on said bail, and a cable having its respective ends operatively connected to the respective drums and intermediate cooperatively with said pulley, whereby the dipper is maintained on an even keel during advance and retractive movements of the dipper while the hoisting drum remains inoperative, and the hoisting drum has normal and uniform influence in hoisting irrespective of advance and retractive movements of the crowd.

7. In a mucking machine having a crowd, a dipper, dipper sticks pivotally connecting the crowd to the dipper, a sheave on said dipper, and hoisting means including a hoisting drum and

driving means therefor, and means for driving said crowd; A compensating drum driven by said crowd and having a peripheral speed equal to twice the lineal speed of said crowd, and a cable 5 having its opposite ends respectively connected to said hoisting drum and said compensating drum and intermediately passing about said pulley or sheave whereby said hoisting drum has normal and uniform effect in hoisting or lowering 10 of the dipper irrespective of the advance or retractive movements of the dipper or the speed of such movements.

8. In a hoisting mechanism for a mucking machine having a dipper, a crowd, and dipper sticks 15 connecting the dipper to the crowd, and hoisting means including a hoisting drum and driving

means therefor and a cable; a rack on said crowd; a pinion cooperating with said rack, and driving means for said pinion; a compensating drum coaxially secured to said pinion and having a rope-pitch diameter equal to twice the pitch diameter 5 of said pinion; a sheave on said dipper; said cable having its opposite ends respectively operatively connected to said hoisting drum and to said compensating drum and intermediately cooperating with said sheave, establishing normal 10 and uniform hoisting effect of the hoisting drum on the dipper irrespective of advance and retractive movements of said crowd and its associated dipper.
